L. JONES

VACUUM LIFTER

Filed Oct. 29, 1927

UNITED STATES PATENT OFFICE.

LEWIS JONES, OF NEW YORK, N. Y.

VACUUM LIFTER.

Application filed October 29, 1927. Serial No. 229,766.

This invention relates to a vacuum cup or vacuum lifter which is particularly adapted for use in lifting and handling smooth sheets of material such as sheets of 5 steel, glass, and the like.

An important object of my invention is to provide a vacuum cup or lifter provided with means for quickly and easily destroying the vacuum when it is desired to within 10 draw the vacuum lifter from the material to which it is applied.

Other objects and advantages of my invention will be apparent from the following description.

15 In the drawing I have shown a preferred embodiment of my invention. In this showing,

Figure 1 is a perspective view of my device showing the relative position of the hand 20 of the operator when the device is used.

Figure 2 is a transverse section, and

Figure 3 is a transverse section showing the relative positions of the vacuum lifter before and after the releasing means is actuated.

Referring to the drawing, the numeral 10 designates generally a conical suction member comprising a body portion 11 and a rim portion 12 formed of resilient material, preferably rubber. Attached to the top of the suction member is a gripping member 13 shaped in the form of a ring. The ring member is joined to the suction member by a neck 14. Extending from the rim 12 to 35 the gripping member 13 are a plurality of flat or round bands 15 which may be made of any desired material such as cord, wire or canvas strips but preferably consist of narrow flat relatively inelastic bands of rubber.

40 While I prefer to make the portion of my vacuum lifter which engages the surface of the article to be lifted, in conical form it will be apparent that it may be made oval or in other shapes without departing from the spirit of my invention since it is the primary purpose of my invention to provide convenient means operable by one or more fingers of the hand operating the lifter for 45 breaking the vacuum therein irrespective of the form or shape of the vacuum member of the device. It also will be apparent that I may employ with some measure of convenience a single vacuum releasing band instead 50 of two as shown in the drawing.

In the operation of my device as employed in lifting steel sheets to separate them from a pack or pile of sheets, the suction device is placed on the middle finger with the palm of the hand preferably extending upwardly. 60 The device is applied to the sheet and pressure exerted thereon to expel air from within the conical member 10. The air pressure on the upper side of the conical member 10 retains the suction device in contact with 65 the sheet. The hand is lifted, thereby raising the sheet a slight distance so that the other hand of the operator may be inserted under the sheet, and the sheet transferred to any desired position. When it is desired 70 to release the suction device from the sheet the operator merely presses upon the outer portion of the bands 15 with the other fingers of the hand, or in other words, simply closes the fingers of the hand together, there- 75 by bending the bands 15 into the dotted line positions as shown in Figure 3 and lifting the rim 12 from contact with the sheet. This allows air to enter within the conical suction member 10, breaks the vacuum therein 80 and releases the suction device from the sheet.

From the foregoing it will be apparent that I have provided a simple suction device which may be quickly and easily released by merely closing the fingers of the hand together and thereby breaking the vacuum within the conical suction member 85 of the vacuum lifter.

Although I have described in detail a preferred form of my invention it is to be understood that changes may be made in the size, shape and arrangement of parts without departing from the spirit of my invention or the scope of the subjoined claim. 90

I claim:

A vacuum lifter adapted for operation on the hand of the user comprising a suction member of resilient material, a ring shaped gripping member connected thereto and having a reduced neck portion, and an elastic band connecting portions of the rim of said suction member at oppositely disposed points with said gripping member, said band being operable by a digit of the hand 100 operating such lifter to raise the edges of 105 the suction member to break the vacuum thereon.

In testimony whereof I affix my signature.
LEWIS JONES.
